mesne assignments, to Steel and Alloy Tank
Company, Newark, N. J., a corporation of New
Jersey

Application March 3, 1950, Serial No. 147,482

14 Claims. (Cl. 139—250)

1

The present invention relates to a loom mechanism for controlling the feed of a rotary hopper or battery carrying the fresh filling bobbins.

In the usual type of automatic loom of fly shuttle type, there is provided a rotary hopper or battery for holding the reserve filling bobbins in a circular series between two discs of said hopper. The hopper is rotated step by step to locate successively the bobbins against a combined stop and bobbin guide, thus presenting them in position for transfer to the shuttle. This stop is so placed that it will check the lowermost bobbin to be transferred in the correct position to be forced out of the hopper and into the shuttle.

The vibration of the loom during its normal operation causes rotation or oscillation of the bobbins in the hopper and more particularly the lowermost one engaged by the stop. This vibration very often causes the end of the filling yarn of the lowermost bobbin to become loose or to wind itself around the usual anchoring means and thus to break. To prevent this situation, comparatively complicated mechanisms have been proposed for holding the lowermost bobbin in the hopper against rotation or oscillation about its axis prior to being transferred into the shuttle.

One object of the present invention is to provide comparatively simple and effective means for positively checking the rotation of the hopper automatically after transfer and after the hopper has been rotated to the next successive bobbin transfer position, without employing the usual bobbin stops or complicated bobbin holding means.

In the usual loom construction, it has been found necessary to employ a heavy spring to stop the transfer mechanism and to return it to its initial position. This spring is also strong enough to rotate the hopper into the next successive transfer. Such a heavy spring is objectionable, since it creates considerable stress and shock and sets up undesirable inertial forces which tend to create vibrations. Such a heavy spring also causes wear on the parts, especially the ratchet and pawl mechanism associated with the step by step feed of the hopper.

A further object is to provide a loom mechanism in which the automatic step by step rotation of the hopper is effected without the use of the usual heavy spring and with minimum of shock even during high speed loom operations.

In conventional loom constructions, the hopper has a manual control device by which the hopper can be released or disconnected from automatic feed. However, the bobbin stop permits manual

2

rotation of the hopper only to the extent to which it is unfilled, as the hopper will always stop when a bobbin reaches said stop. As a result, the filling of the hopper is difficult to accomplish from the front of the loom.

A further object of the present invention is to provide a new and improved hopper feed and control device which is automatic in operation, but which can be manually operated and controlled to rotate the hopper selectively in any rotative position independently of the number of bobbins therein and to effect thereby easy filling of the hopper from the front of the loom.

A still further object is to provide a new and improved manual hopper feed control device which is operable to render transfer ineffective without shutting down the loom.

Various other objects of the invention are apparent from the following particular description and from an inspection of the accompanying drawings, in which:

Fig. 1 is a rear detail view of the battery side of the loom showing the hopper feed and control mechanism embodying the present invention;

Fig. 2 is a section of the hopper feed and control mechanism taken approximately along lines 2—2 of Fig. 1 and showing said mechanism during normal operations, while no transfer is indicated and the hopper is locked;

Fig. 3 is a section similar to that of Fig. 2, but showing the hopper feed and control mechanism after transfer has been indicated and at the instant transfer of a fresh bobbin from the hopper to the shuttle has been effected;

Fig. 4 is a section similar to that of Fig. 2, but showing in full lines the hopper feed pawl dropped into a lower interdental space of the ratchet gear after transfer has been completed, and in dot and dash lines said pawl advanced to rotate the ratchet gear one step into the next transfer position;

Fig. 5 is a section of the hopper feed and control mechanism taken approximately along lines 5—5 of Fig. 1 and shown in position during normal operations before transfer is indicated, the manual feed control for the hopper being shown in full lines in inoperative position and in dot and dash lines in releasing position to permit manual rotation of the hopper and to lock the bobbin transfer mechanism against operation; and

Fig. 6 is a section of the hopper feed and control mechanism similar to that of Fig. 5, but shows this mechanism while transfer is indicated.

55

and while the manual control device is in releasing position to permit manual rotation of the hopper and to lock the transfer mechanism against operation.

Referring to the drawings, the reserve bobbins 10 on which the filling yarn is wound are carried in a circular series in a rotatable hopper or magazine 11. The hopper 11 is on the right hand side of the loom and comprises a stationary plate 12 secured to a hopper stand 13 which in turn 10 is affixed to the part of the breast beam (not shown) on the right loomside 15. The hopper stand 13 carries a bearing support 16 for a hopper shaft 17 to which a pair of axially spaced bobbin supporting discs are affixed in any suitable manner for rotation in unison (only the inner one 18 of said discs being shown).

Connected directly to the outer side of the outer bobbin supporting disc (not shown) is a suitable peripherally notched thread guide (not shown) cooperating with a thread holder in a manner known in the art.

For releasably supporting the heels or butts of the bobbins 10 in the inner disc 18, said disc has a ring (not shown) with a series of circumferentially spaced peripheral recesses in which the respective heels of the bobbins 10 are inserted. The heels of the bobbins project beyond the inner disc 18 outside of the space between the two bobbin supporting discs.

For releasably supporting the tips of the bobbins in the outer supporting disc (not shown), said disc has a ring with a series of peripheral recesses in alignment with respective recesses in the disc 18. With the arrangement described, the bobbins are supported with their heels or butts extending between the stationary plate 12 and the rotary disc 18. The hopper device so far described, forms no part of the present invention, and may be of any other well known construction.

The operation of the transfer mechanism is controlled by a starting rod 30 supported in journals 31 on the right loomside 15. Whenever substantial exhaustion of the filling is indicated by a feeler (not shown) at the left-hand side of the loom, a partial revolution is given to the starting rod 30. This sets the transfer mechanism into operation, while the lay 32 along which the shuttle 33 is thrown is moving rearward, and the shuttle is approaching the shuttle box 34 on the battery side of the loom.

The actual transfer of the lowermost fresh bobbin 10 in the hopper 11 is effected by a transfer mechanism which per se forms no part of the present invention, but which is fully disclosed and claimed in copending application Serial No. 147,483, filed March 3, 1950. This transfer mechanism comprises in general a main transfer 45 and an auxiliary transfer (not shown) operable in unison by the motion of the lay 32, to engage the heel and tip section respectively of the bottom bobbin 10 and to force thereby said bobbin out of the hopper and against the spent bobbin in the shuttle 33. The fresh 50 bobbin, while being pressed into the top of the shuttle 33 forces the empty bobbin therein out through the bottom of the shuttle and into a suitable receptacle (not shown).

The main transfer 35 comprises an arm 40 70 pivotally mounted on a stud or pin 41 on the hopper stand 13 and located outside the hopper 11 beyond the stationary plate 12. The transfer arm 40 has a transverse extension 42 passing through a slot (not shown) in the stationary 75

plate 12 and terminating at its outer end in a shoe or head 43 between said plate and the rotary disc 18. This transfer head is adapted to engage the heel of the lowermost bobbin in the hopper 11 during transfer. A spring 39 returns the transfer arm 40 into the inactive position shown in Fig. 2.

The auxiliary transfer (not shown) comprises an arm extending into the space between the two rotary bobbin supporting discs of the hopper 11 and mounted on a hollow shaft 48 for engagement with the bobbin near its tip. This shaft is mounted for rocking movement on a bearing or axle rod 49 affixed to a support on the hopper stand 13 and is operated in unison with the main transfer arm 40 by means disclosed fully in the aforesaid copending application.

To prevent transfer of the fresh bobbin when the shuttle 33 is not properly in the shuttle box 34, there is provided a shuttle feeler device comprising a tubular guide 50 secured to a bracket 51 affixed to and depending from the base 52 of the stand 13. Slidable in the guide 50 is a feeler plunger 53 carrying a pin 54 extending through diametrically opposed elongated slots 55 in said guide. The projecting ends of the pin 54 are engaged by the forked prongs of an arm 56 affixed to a suitably journaled pivot shaft 57.

The feeler plunger 53 is operated from the starting rod 30 through the pivoted arm 56 when transfer is indicated. For that purpose, the starting rod 30 has rigidly connected thereto a crank arm 60 pivotally connected at its outer end to one end of a giveaway or lost-motion link 61, the other end of said link being connected to the pivoted arm 56.

For operating the two transfer arms including the main transfer arm 40 for bobbin transfer when transfer is indicated and to effect protection through operation of the shuttle feeler device therein, there is provided a bell crank 65 pivoted to an extension of the bracket 51 and having two arms 66 and 67. One of the crank arms 66 is connected to the main transfer arm 40 by a link 68 pivotally connected at its ends to said arms 66 and 40 respectively. The other crank arm 67 pivotally carries a latch finger 71 adapted to be engaged by a bunter 72 on the forward side of the lay 32 during the forward movement of the lay, after transfer has been indicated and the shuttle feeler has cleared the mechanism for transfer. The bunter 72 has a V-shaped groove 73 and the outer end of the latch finger 71 is correspondingly bevelled for retention into said groove during transfer.

The latch finger 71 is moved into and out of protective position through the feeler slide movement of the feeler plunger 53 in the guide 50. For that purpose, there is an extensible spring link connection 76 between the latch finger 71 and the feeler plunger 53. This spring connection is such, that when no transfer is indicated, and the feeler plunger 53 is in the withdrawn inactive position shown in Fig. 2, the latch finger 71 is held by said link connection in depressed position in which position it is out of the path of reciprocating movement of groove 73 of the lay bunter 72 and in line with the cut out portion 74 of said bunter. When transfer is indicated, and the feeler plunger 53 has been moved into shuttle feeler position shown in Fig. 3, the latch finger 71 will be lifted into the path of movement of the groove 73 of the bunter 72 by the spring link connection 76. Consequently, as the lay 32 moves forward towards front center position, its move-

ment is transmitted to the bell crank 65. This bell crank rotating clockwise (Fig. 3) thereby swings the main transfer arm 40 through the link 68 about the axis of its pivot support 41 into bobbin transfer position. At the same time, the auxiliary transfer arm (not shown) swings about the bearing rod 49 to assist in the transfer of the bobbin, as described in the aforesaid copending application.

The feed mechanism for automatically rotating the hopper 11 one step after each transfer operation and for bringing the next fresh bobbin into transfer position and the control device for releasing this mechanism to permit continuous manual rotation of the hopper constitute the subject of the invention intended to be covered by the present application. This hopper feed mechanism comprises a ratchet gear 80 affixed by studs or bolts 81 to the outer side of the bobbin supporting disc 18 of the hopper between said disc and the stationary plate 12 and keyed to the hopper shaft 17. This ratchet gear is operated by a feed pawl 82 pressed into mesh engagement with a tooth of said gear by a coil spring 83 connected to said pawl and to the plate 12. This feed pawl is pivotally secured by a pivot stud or pin 84 to one end of a lever arm 85 pivotally mounted intermediate its ends to the hopper stand 13 by a pivot stud 86. The other end of the lever arm 85 has secured thereto a tail comprising a spring bumper 87 adapted to be engaged by a lay sword 88 during its return movement rearward after completion of transfer. This causes the lever arm 85 to turn about its pivot support 86 into hopper feeding position.

A stop pawl 100 pivotally mounted at 101 to stop block 102 secured to the stationary plate 12 is pressed into tooth engagement with the ratchet gear 80 by a coil spring 103 attached to said pawl and to the stationary plate 12. The pawl 100 serves to hold hopper 11 in position against counterclockwise rotation (Fig. 2). The pawl 100 is cam-shaped at its tooth engaging end so that it is moved automatically out of the interdental space of the ratchet gear 80 when hopper 11 is rotated clockwise by a force sufficient to overcome the pull of spring 103. The pull of spring 103 is sufficient to hold the hopper 11 in position when pawl 82 is taken out of engagement with ratchet gear 80 prior to clockwise rotation of hopper 11, as will be later explained, for loading purposes.

The stop block 102 has its bottom corner adjacent ratchet gear 80 cut away as shown in Fig. 3 to engage the top of pawl 82 so that when the pawl 82 is in locking position (Fig. 2) the pawl 82 is wedged between the stop block 102 and the ratchet gear 80 to prevent clockwise rotation of the hopper 11.

The feed pawl 82 is made to take up a tooth on the ratchet gear 80 after transfer by the action of a link 90 pivotally connected at one end at 91 to the main transfer arm 40, and pivotally attached at its other end to the lever arm 85 by a lost-motion connection comprising an elongated slot 92 on said link extending lengthwise thereof and slidably receiving a pin 93 fastened to said lever arm. This lost-motion connection 92, 93 serves to initiate operation of the hopper feed mechanism near the later phases of bobbin transfer.

During the final stages of each bobbin transfer operation, the link 90 rotates the lever arm 85 about the pivot stud 86 and into position to cam the feed pawl 82 out of engagement with a tooth

of the ratchet gear 80 and to cause it to fall downwards and by the action of the spring 83 forwards into engagement with the next tooth of said ratchet gear. During the return rearward movement of the lay 32, the sword 88 engaging the spring bumper 87 secured to the lever arm 85 imparting clockwise rotation to said arm, the rotation being stopped when feed pawl 82 is wedged between stop block 102 and ratchet gear 80. This wedged position accurately locates hopper 11 for the next transfer.

The spring bumper 87 is shown comprising a pair of leaf springs secured to the lever arm 85 by bolts 95 and disposed on one side of the lay sword 88. A bracket 96 secured to the lay sword 88 carries a bunter 97 extending over the spring bumper 87. The lay sword 88 is mounted for rocking angular movement about a lower support, so that the bunter 97 carried by said lay sword moves gradually downward as it moves rearward of the loom.

As the lay 32 moves rearward after completion of transfer, the bunter 97 on the lay sword 88 engaging the spring bumper 87 moves said bumper downward. This causes the feed pawl 82 to rotate the hopper 11 clockwise one tooth step into the next transfer position as described.

A manual control device serves to disconnect the automatic hopper feeding mechanism to lock the transfer mechanism against operation and to disengage the feed pawl 82 from the ratchet gear 80, so that the hopper 11 may be turned back by hand, as when inserting fresh bobbins. This manual control device comprises a hand lever 110 pivotally mounted at 111 to the stationary plate 12 and projecting beyond the edge thereof, to afford easy accessibility to said hand lever. This hand lever is normally urged by a coil spring 112 into inoperative position against an upper stop 40 113 on the stationary plate 12.

The end of the lever arm 85 near the feed pawl 82 has an edge surface 114 located directly below the edge of the hand lever 110 and adapted to be engaged by said latter edge when said hand lever is pressed downward. This downward movement of the hand lever 110 causes the lever arm 85 to turn about its pivot support 86 and to move thereby the feed pawl 82 out of tooth engagement with the ratchet gear 80. A lower stop 115 for the hand lever 110 limits the turning movement of the lever arm 85 so that the feed pawl 82 moves out of one interdental space on the ratchet gear 80 but does not move into the next interdental space. The lower stop 115 prevents such rotation of arm 85 as would carry bumper 87 into the path of the lay 32 which condition would be undesirable during manual rotation of the hopper 11. While the hand lever 110 is depressed downward against the lower stop 115, the ratchet gear 80 is released from engagement with the feed pawl 82 so that it may be rotated clockwise (Fig. 2) continuously, as for example to fill the hopper 11.

The means for locking the transfer mechanism against operation when the hand lever 110 is depressed comprises a rod 120 pivotally attached to and depending from said hand lever and guided for endwise movement in a groove 121 in the hopper stand 13. The lower end of this rod is adapted to extend into a hole 122 in the pivot shaft 57 on which the arm 56 for operating the shuttle feeler plunger 53 is secured. When the feeler plunger 53 is in withdrawn inoperative position shown in Figs. 5 and 6, the shaft hole 75 122 is in alignment with the lower end of the rod

120 and is, therefore, in position to receive said rod when lowered therein by depressive manipulation of the hand lever 110. This manipulation causes the pivot shaft 57 to be locked against rotation and renders thereby the transfer mechanism inoperative. Continuous rotation of the hopper 11 clockwise (Fig. 2) can consequently be effected manually with safety and with assurance that the transfer mechanism will not be operated in the meantime.

Operation

Although the operation of the apparatus of the present invention is obvious from the foregoing description, this operation is herein summarized:

While the loom is normally operating as shown in Fig. 2 and the yarn supply on the running shuttle is ample, the starting rod 30 will be in the rotative position shown, the latch finger 71 will be depressed out of the path of movement of the lay bunter 72 and the shuttle feeler plunger 53 will be withdrawn in its guide 50. In this inactive position of the starting rod 30, the main transfer arm 40 will be in elevated position directly above the lowermost bobbin 10 in the hopper 11, the stop pawl 100 will be in the position shown to lock the ratchet gear 80 and, therefore, the hopper 11 against rotation counterclockwise, while permitting clockwise rotation of said gear and hopper, and the feed pawl 82 will be in position to lock said ratchet gear and, therefore, the hopper against clockwise rotation. The hopper 11 will thereby be positively locked during normal operations against the effect of loom vibrations, without the use of bobbin stops or complicated bobbin holding devices.

Upon the receipt of a transfer impulse from a suitable filling feeler mechanism near the left side of the loom indicating substantial exhaustion of the filling, the starting rod 30 will be partially rotated counterclockwise from the position shown in Fig. 2 to that shown in Fig. 3. This operation is effected while the lay 32 is moving towards the front of the loom (towards the left in Figs. 2 and 3), and while the shuttle 33 approaches the box 34 on the magazine side of the loom, and causes the pivoted arm 56 to swing counterclockwise and the feeler plunger 53 just beyond the end of the shuttle to be shifted in its guide 50 to the right. This movement of the feeler plunger 53 raises the latch finger 71 through the extensible connection 76 from its depressed inactive position shown in Fig. 2 to the raised operative position in the path of movement of the lay bunter 72 shown in Fig. 3.

As the lay 32 arrives at its rearmost point and then commences its forward movement and the shuttle terminates its flight into the box 34, the open end of the box 34 just beyond the tip of a properly boxed shuttle 33 moves past the shuttle feeler tip, so that the feeler plunger 53 will remain in the projected position shown in Fig. 3, while the lay moves forward toward front center position (toward the left in Fig. 3).

Upon continued forward movement of the lay 32, the bunter 72 thereon will engage the raised latch finger 71 as shown in Fig. 3, and will rotate the bell crank 65 clockwise about its pivot support, causing thereby depressing angular movement of the main transfer arm 40 clockwise about its pivot support 41 through the link 68 and at the same time depressing movement of the auxiliary transfer arm (not shown), in the manner indicated in the aforesaid application. The extensibility of

the link connection 76 through its spring permits this clockwise rotation of the bell crank 65.

The movement of the transfer arms as described will cause the bottom bobbin to be ejected from the hopper 11 and to be delivered into the shuttle 33, while the spent bobbin is forced out of the shuttle by its engagement with the incoming bobbin, as shown in Fig. 3.

During the final stages of the angular movement of the main transfer arm 40 into transfer position shown in Fig. 3, the link 90 being pulled downward, causes the lever arm 85 to rotate counterclockwise about its pivot support 86. By this operation, the feed pawl 82 slides out of one interdental space of the ratchet gear 80 and is moved downward and rearward into the next interdental space as shown in full lines in Fig. 4.

After bobbin transfer has been completed, the lay 32 starts moving rearwardly (towards the right in Figs. 2 and 3) of the loom as a result of the rearward angular movement of the lay swords. During this rearward movement of the lay 32, the bunter 97 on the lay sword 88 strikes the bumper spring 87 which is substantially horizontal and positively rotates the lever arm 85 clockwise into the position shown in dot and dash lines in Fig. 4, causing thereby the feed pawl 82 to turn positively the ratchet gear 80 one tooth step and the hopper 11 to rotate correspondingly at a comparatively slow rate proportional to the speed of the lay 32. This operation brings the next bobbin on the hopper 11 into transfer position in preparation for the next transfer operation.

While the ratchet gear 80 is being rotated clockwise into the next transfer position, the stop pawl 100 is being cammed out of one interdental space into the next one. The snapping of this stop pawl into this next interdental space by the action of the spring 103, serves as a brake on the ratchet gear 80 preventing it from overriding beyond one tooth step.

It should be noted that although the transfer arm 40 is returned by the strong powerful spring 39 into inactive position, the lost-motion connection 92, 93 between the link 90 and the lever arm 85 is such that this spring has no effect on the feed of the ratchet gear 80. The pawl and ratchet parts of the hopper feed mechanism are, therefore, not subjected to shock and excessive wear resulting from the impact or shock of such a spring, since the feed movement of the ratchet gear 80 is effected more gradually and smoothly from the movement of the lay sword 88 through the engagement of the bunter 97 on said sword with the spring bumper 87 on the lever arm 85.

If during normal operations of the loom while the feeler plunger 53 is in the inoperative withdrawn position shown in Fig. 5 and the pivot shaft 57 for the arm 56 is in the rotative position shown, it is desired to rotate the hopper 11 clockwise, the hand lever 110 is depressed from the position shown in full lines to the position shown in dot and dash lines. This will causes the transfer locking rod 120 to be lowered into the hole 122 in the pivot shaft 57, thereby locking shaft in position to prevent operation of the shuttle feeler 53 and preventing operation of the transfer mechanism. At the same time, the lever arm 85 is turned about its pivot support 86 just sufficiently to effect disengagement of the feed pawl 82 from the ratchet gear 80 but not enough to cause leaf spring 87 to contact bunter 97. Since there is no bobbin stop or guide, the hopper 11 can be rotated continuously counterclockwise (Fig. 5) while the hand lever 110 is depressed regardless of the

number of bobbins in said hopper, provided the auxiliary transfer arm (not shown) has been withdrawn in position to prevent blocking of said hopper, as described in the aforesaid copending application. The hopper may thereby be filled entirely from the front of the loom regardless of the number of bobbins in the hopper.

If while the hand lever 110 is depressed, a transfer impulse is received and the starting rod 30 is partially rotated from the position shown in Fig. 5 to that shown in Fig. 6, this is ineffective for transfer, since the pivot shaft 57 controlling the operation of the shuttle feeler 53 is locked by the rod 120. The giveaway or lost-motion characteristics of the link 61 permits rotation of the starting rod 30 without operating the shuttle feeler, as shown in Fig. 6.

While the invention has been described with particular reference to a specific embodiment, it is to be understood that it is not to be limited thereto, but is to be construed broadly and restricted solely by the scope of the appended claims.

What is claimed is:

1. In a loom, a lay for a shuttle, a rotary hopper, a mechanism for transferring fresh bobbins successively from said hopper into the shuttle and comprising a transfer arm adapted to engage a bobbin on said hopper and movable to eject it therefrom towards the shuttle, and means for rotating said hopper step by step to bring the bobbins thereon successively into transfer position with respect to said transferring mechanism at the end of each bobbin transfer operation and comprising a ratchet gear connected for rotation with said hopper, a lever arm mounted for angular movement about a pivot axis, a feed pawl for said ratchet gear supported on said lever arm and adapted to be moved from one interdental space of said gear to another as said lever arm moves angularly in one direction about its pivot axis, a link connection between said arms for moving said lever arm in said direction about its pivot axis as said transfer arm enters into the late phases of its transfer operation, and a transmission between said lay and said lever arm for turning said lever arm about its pivot axis and in the opposite direction to rotate said ratchet gear one step at the end of each bobbin transfer operation.

2. In a loom, a lay for a shuttle, a rotary hopper, a mechanism for transferring fresh bobbins successively from said hopper into the shuttle and comprising a transfer arm adapted to engage a bobbin on said hopper and movable to eject it therefrom towards the shuttle, and means for rotating said hopper step by step to bring the bobbins thereon successively into transfer position with respect to said transferring mechanism at the end of each bobbin transfer operation and comprising a ratchet gear connected for rotation with said hopper, a lever arm mounted for angular movement about a pivot axis, a feed pawl for said ratchet gear supported on said lever arm and adapted to be moved from one interdental space of said gear to another as said lever arm moves angularly in one direction about its pivot axis, a link pivotally connected to said transfer arm and having a lost-motion pivotal connection with said lever arm for moving said lever arm in said direction about its pivotal axis as said transfer arm is moving in the late phases of its transfer operation, said lost-motion connection permitting said transfer arm to return towards inactive position without transmitting its

return movement to said lever arm, and means for transmitting the movement of said lay to said lever arm to move it about its pivot axis in the opposite direction to rotate said ratchet gear one step.

5. In a loom, a lay for a shuttle, a rotary hopper, a mechanism for transferring fresh bobbins successively from said hopper into the shuttle, and means for rotating said hopper step by step 10 to bring the bobbins thereon successively into transfer position with respect to said transferring mechanism at the end of each bobbin transfer operation and comprising a feed member for transmitting rotary motion to said hopper, and spring bumper means between said lay and said member for transmitting the movement of said lay to said member and for rotating thereby said hopper one step.

15 3. In a loom, a lay for a shuttle, a rotary hopper, a mechanism for transferring fresh bobbins successively from said hopper into the shuttle, and means for rotating said hopper step by step 20 to bring the bobbins thereon successively into transfer position with respect to said transferring mechanism at the end of each bobbin transfer operation and comprising a feed member for transmitting rotary motion to said hopper, and spring bumper means between said lay and said member for transmitting the movement of said lay to said member and for rotating thereby said hopper one step.

25 4. In a loom, a lay for a shuttle, a rotary hopper, a mechanism for transferring fresh bobbins successively from said hopper into the shuttle, and means for rotating said hopper step by step 20 to bring the bobbins thereon successively into transfer position with respect to said transferring mechanism at the end of each bobbin transfer operation and comprising a ratchet gear connected for rotation with said hopper, a feed pawl for said ratchet gear, means operable from said transfer mechanism for moving said pawl from one interdental space of said gear to another, a spring bumper, bunter means connected to said lay and movable therewith for engaging said spring bumper and actuating it after said pawl has been moved from one gear space to another, and transmission means between said spring bumper and said pawl to move said pawl into position to rotate said hopper one step upon actuation of said bumper.

30 5. In a loom, a lay for a shuttle, a rotary hopper, a mechanism for transferring fresh bobbins successively from said hopper into the shuttle, and means for rotating said hopper step by step 30 to bring the bobbins thereon successively into transfer position with respect to said transferring mechanism at the end of each bobbin transfer operation and comprising a ratchet gear connected for rotation with said hopper, a level arm mounted for angular movement about a pivot axis, a feed pawl for said ratchet gear supported on said lever arm and adapted to be moved from one interdental space of said gear to another as said lever arm moves angularly in one direction about its pivot axis, means for moving said lever arm in said direction about its pivot axis near completion of each transfer operation, and means 35 connected to said lay and movable therewith for engaging said lever arm after said pawl has been moved from one gear space to another, and moving it about its pivot axis in an opposite direction to rotate said hopper one step.

40 6. In a loom, a lay for a shuttle, a rotary hopper, a mechanism for transferring fresh bobbins successively from said hopper into the shuttle, and means for rotating said hopper step by step 40 to bring the bobbins thereon successively into transfer position with respect to said transferring mechanism at the end of each bobbin transfer operation and comprising a ratchet gear connected for rotation with said hopper, a lever arm mounted for angular movement about a pivot axis, a feed pawl for said ratchet gear supported on said lever arm and adapted to be moved from one interdental space of said gear to another as said lever arm moves angularly in one direction about its pivot axis, means for moving said lever arm

arm in said direction about its pivot axis near completion of each transfer operation, a spring bumper secured to said lever arm, and a bunter movable with said lay and mounted in position to engage said spring bumper after said pawl has been moved from one gear space to another and to move said lever arm in an opposite direction to rotate said hopper one step.

7. In a loom, a lay for a shuttle rockable angularly about a center located below said lay, whereby said lay drops gradually as it moves rearward, a rotary hopper, a mechanism for transferring fresh bobbins successively from said hopper into the shuttle, and means for rotating said hopper step by step to bring the bobbins successively into transfer position with respect to said transferring mechanism at the end of each bobbin transfer operation and comprising a ratchet gear connected for rotation with said hopper, a lever arm mounted for angular movement about a pivot axis, a feed pawl for said ratchet gear supported on said lever arm and adapted to be moved from one interdental space of said gear to another as said lever arm moves angularly in one direction about its pivot axis, said lever arm having a tail extending substantially horizontally when said lever arm has been moved into position to displace said pawl into said latter gear space, means for moving said lever arm in said direction and into said position near the end of each transfer operation and a bunter movable with said lay and adapted during the rearward movement of said lay to engage said tail and to turn thereby said lever arm about its pivot axis and in the opposite direction to rotate said ratchet gear one step.

8. In a loom, the combination as described in claim 7, said lever arm tail comprising a spring leaf bumper.

9. In a loom, a lay for a shuttle, upright swords for said lay supported for angular rocking movement about a center located below said lay, whereby said swords drop gradually at their upper sections as they move rearwardly of the loom, a mechanism for transferring fresh bobbins successively from said hopper into the shuttle, and means for rotating said hopper step by step to bring the bobbins successively into transfer position with respect to said transferring mechanism at the end of each bobbin transfer operation and comprising a ratchet gear connected for rotation with said hopper, a lever arm mounted for angular movement about a pivot axis, a feed pawl for said ratchet gear supported on said lever arm and adapted to be moved from one interdental space of said gear to another as said lever arm moves angularly in one direction about its pivot axis, said lever arm having a tail extending substantially horizontally when said lever arm has been moved into position to displace said pawl into said latter gear space, means for moving said lever arm in said direction and into said position near the end of each transfer operation, and a bunter connected to the upper section of one side of one of said swords above said lever arm tail and adapted during the rearward movement of said lay to engage said tail and to turn thereby said lever arm about its pivot axis and in the opposite direction to rotate said ratchet gear one step.

10. In a loom, a rotary hopper, a mechanism for transferring fresh bobbins successively from said hopper into a shuttle and comprising a rotary shaft controlling the operation of said mechanism, means for automatically rotating

said hopper step by step to bring the bobbins thereon successively into transfer position with respect to said transferring mechanism at the end of each bobbin transfer operation, means for locking said hopper against rotation until the next bobbin transfer operation, manually controlled means for releasing said locking means to permit said hopper to be rotated manually, and means operable when said hopper is under manual control for automatically locking said shaft against rotation and for rendering thereby said transfer mechanism inoperative.

11. In a loom, a rotary hopper, a mechanism for transferring fresh bobbins successively from said hopper into a shuttle and comprising a rotary shaft controlling the operation of said mechanism, means for automatically rotating said hopper step by step to bring the bobbins thereon successively into transfer position with respect to said transferring mechanism at the end of each bobbin transfer operation, a hand lever, means responsive to the actuation of said hand lever in one direction from inactive position for releasing said locking means to permit said hopper to be rotated manually, and a connection between said hand lever and said rotary shaft for automatically locking said shaft against rotation and for rendering thereby said transfer mechanism inoperative when said hand lever is actuated in said direction from said inactive position, said connection being automatically released from said shaft to permit said shaft to operate when said hand lever is returned to said inactive position.

12. In a loom, the combination as described in claim 11, said shaft having a hole transversely thereof, said connection comprising a rod connected to said hand lever and movable into and out of said shaft hole as said hand lever is actuated to lock or unlock said shaft.

13. In a loom, a rotary hopper, a mechanism for transferring fresh bobbins successively from said hopper into a shuttle and comprising a starting rod adapted to be partially rotated when transfer is indicated, a pivot shaft, an arm connected to said pivot shaft for operating a shuttle feeler, and a connection between said starting rod and said arm to swing said arm about the axis of said pivot shaft as said starting rod is partially rotated by a transfer indication, means for automatically rotating said hopper step by step to bring the bobbins thereon successively into transfer position with respect to said transferring mechanism at the end of each bobbin transfer operation, means for locking said hopper against rotation until the next bobbin transfer operation, a hand lever, means responsive to the actuation of said hand lever in one direction from inactive position for releasing said locking means to permit said hopper to be rotated manually, and a connection between said hand lever and said pivot shaft for automatically locking said shaft against rotation and for rendering thereby said transfer mechanism inoperative when said hand lever is actuated in said direction from said inactive position, said connection being automatically released from said shaft to permit said shaft to operate when said hand lever is returned to said inactive position.

14. In a loom having a lay, a rotary hopper, a mechanism for transferring fresh bobbins successively from said hopper into a shuttle and comprising a pivoted transfer arm, means for rotating said hopper automatically in a feeding

direction one step after every bobbin transfer operation, and comprising a ratchet gear connected to said hopper for rotation therewith, a lever arm separate from said transferring mechanism but operated therefrom, said lever arm being supported for turning movement about a pivot axis, a feed pawl pivotally connected to one end section of said lever, spring means yieldably pressing said pawl into mesh engagement with said ratchet gear, a link between said transfer arm and said lever arm for turning said lever arm about its pivot axis in one direction, said pawl being adapted to be displaced from one interdental space of said ratchet gear to another when said lever arm is turned in said latter direction, and means for engaging the other end section of said lever arm by a member movable with said lever after transfer has been completed to turn said lever arm about its pivot

5 axis in an opposite direction, said pawl being adapted to turn said ratchet gear one step when said lever arm is turned in the latter direction, and a hand lever adapted to engage said lever arm upon actuation to move said feed pawl out of mesh engagement with said ratchet gear.

KAROL KULCZYCKI.
